UNITED STATES PATENT OFFICE.

GEORGE H. WHITTINGHAM, OF BALTIMORE, MARYLAND, ASSIGNEE TO MONITOR CON-
TROLLER COMPANY, OF BALTIMORE, MARYLAND, A CORPORATION OF MARY-
LAND.

THERMOSTATIC DEVICE.

Application filed March 17, 1924. Serial No. 699,955.

To all whom it may concern:

Be it known that I, GEORGE H. WHITTINGHAM, a citizen of the United States, residing at Baltimore, in the State of Maryland, have invented certain new and useful Improvements in Thermostatic Devices, of which the following is a specification.

This invention relates to a thermally operated device for controlling switches in an electric circuit, although it may be used for a variety of other purposes. The invention comprises a closed metal tube filled with an expansible liquid and having two sections, one corrugated and expansible by the pressure of the liquid, and the other relatively inextensible by the liquid pressure. The device is mounted upon a suitable support, with the expansible section below the inextensible section, and a heating element is arranged adjacent the inextensible section. With this arrangement, the heat is applied to the liquid through the upper inextensible section only, and the expansion of the liquid in this section causes the forcible expansion of the lower section which is not directly affected by the heat from the heating element. This arrangement gives greater precision to the operation of the expansible section than if the heat were applied directly to it. In the preferred arrangement, a heating coil is arranged around the upper section of the tube, and this coil is surrounded by a housing, of heat insulating material, which has openings to permit of the upward circulation of air through the housing to carry off the heat and permit the coil and the tube to cool when the current in the coil decreases or is cut off. The heated air thus travels in a direction away from the expansible section of the tube, and this latter section is also preferably shielded from the heating element by a shelf which forms an abutment for said section.

In the accompanying drawing,

Fig. 1 is a front elevation, partly in section, of a unit comprising two thermally operated devices embodying my improvements and arranged to actuate a switch lever which is common to the two devices;

Fig. 2 is a side elevation of the same; and, Fig. 3 is a top plan view of the same.

Referring to the drawing, *a* indicates a suitable base upon which is secured a sheet metal back-piece 1, having attached to its

upper end a shelf 2 of insulating material which projects forwardly from the base. The metal back-piece has a forward projection 3 at its lower end upon which is pivotally mounted an elbow lever 4. A spring 5, interposed between the shelf 2 and the shorter arm 4^a of the lever, constantly tends to hold the end 4^b of the longer arm of the lever against a contact member 6 on the forward edge of the shelf. The lever 4 constitutes one arm of a switch, which is normally closed against the contact 6. Threaded bushings 7 are adjustably arranged in openings in the shelf, and thermostatic tubes 8 extend through these bushings. These tubes are of relatively thin metal and closed at their ends and filled with an expansible liquid 9. Each tube comprises a corrugated section 10, adapted to be expanded by the expansive force of the liquid, and a plain section 11, which is inextensible by the force of the liquid. A shoulder 12^a is provided on the tube at the junction of the two sections and this shoulder fits against a shoulder 12^b, within the bushing 7. The corrugated section of the tube is interposed between said shoulder and the horizontal part 4^c of the longer arm of the lever 4. The plain section of the tube extends upwardly above the shelf 2 and is surrounded by a heating coil 13, which is enclosed within a two-part housing 14, which housing is made of insulating material and closely surrounds the tube and holds the coil in a position which is substantially concentric with the axis of the tube. The housing is composed of two similar members 14^a, provided with lugs 14^b and secured together by screws 15 which pass through the lugs and into posts 16 which are attached to a block 17, secured to the base *a*. As shown best in Fig. 3, the ends of the housing are provided with heads 18 which have central openings to receive the tube, and radial slots 19 for permitting the air to flow upwardly through the housing to cool the coil and tube when the current in the coil is reduced or cut off. As shown in the drawing, the ends of each coil are connected to suitable binding posts 20 which may be connected to the current source. It is to be noted that with the arrangement described, the expansion section of each tube is below the heating element and also shielded from it by the shelf, and

that the heat is applied directly only to the upper inexpandable part of the tube.

In operation, the liquid in the upper part of the tube becomes heated by heat from the surrounding coil and as the liquid expands with heat, the corrugated section 9 of the tube is forcibly expanded by the liquid and presses the switch arm or lever 4 to open position against the tension of the spring 5. By adjusting the sleeve or socket 7 upwardly or downwardly, the tube will be allowed to expand to a greater or less extent before causing the actuation of the switch. When the current in the heating coil falls or is cut off, the upper part of the tube and the liquid therein will cool and the expandable portion of the tube will then contract and permit the switch to close. In order that the device may work properly, the heat should be prevented from accumulating in the housing surrounding the tube, and for this purpose the openings 17 are provided in the heads of the housing so that the excess heat will be carried off by the upward flow of air through the housing. This upward flow also carries the heat in the direction away from the expandable section of the tube, which is desirable, since it is the purpose to have this section operate by the expandable force of the liquid rather than by the heating of the section, or of the liquid therein.

It will be understood from the arrangement shown in the drawing that the switch lever will be operated by the expansion of either of the tubes. Thus, if the coils be connected in different legs of a multi-phase motor circuit, an excessive current flowing in either leg will cause the action of the switch. This is one purpose of the invention. It will be obvious that the invention may be applied to various uses.

What I claim is:

1. The combination with suitable supporting means, of a thermostatic device mounted

thereon and comprising a closed tube filled with an expandable liquid, said tube having a lower corrugated section expandable longitudinally by the pressure of the liquid and a relatively inexpandable upper section, a heating coil surrounding said upper section, and a shield of insulating material between said coil and the lower section.

2. The combination with suitable supporting means, of a thermostatic device mounted thereon and comprising a closed tube filled with an expandable liquid, said tube having a lower corrugated section expandable longitudinally by the pressure of the liquid and a relatively inexpandable upper section, and a heating coil surrounding said upper section.

3. The combination with suitable supporting means, of a thermostatic device mounted thereon and comprising a closed tube filled with an expandable liquid, said tube having a lower corrugated section expandable longitudinally by the pressure of the liquid and a relatively inexpandable upper section, a heating coil surrounding said upper section, and a housing surrounding said coil, said housing having openings to permit the upward circulation of air therethrough.

4. The combination with suitable supporting means, of a thermostatic device mounted thereon and comprising a closed tube containing an expandable liquid, said tube having a lower corrugated section expandable longitudinally by the pressure of the liquid and a relatively inexpandable upper section, a heating coil surrounding said upper section and a housing surrounding said coil and adapted to hold the same in concentric position with respect to the axis of the tube, said housing having openings to permit circulation of air therethrough.

In testimony whereof I hereunto affix my signature.

GEORGE H. WHITTINGHAM.
